METHOD FOR REMOVING PARAFFIN DEPOSITS

Wilfred S. Crake, Houston, Tex., assignor to Shell Development Company, Emeryville, Calif., a corporation of Delaware

Application April 24, 1951, Serial No. 222,709

1 Claim. (Cl. 166—43)

This invention relates to the production of oil from a well and pertains more particularly to an improved method for removing paraffin and asphaltic deposits from an oil well.

It is well recognized that in some oil-producing areas the oil may contain a substantial amount of a waxy constituent, such as paraffin, which is in the liquid state when at the bottom-hole well temperature and pressure. As the oil is pumped or allowed to flow up the production tubing to the top of the well, the temperature of the oil gradually decreases until a point is reached at which the paraffin crystallizes out and accumulates on the inside walls of the tubing. In time, the paraffin accumulation continues to build up until the volume of production from the well is materially reduced or stopped entirely. The operator of the well is then faced with the problem of removing the paraffin, the removal thereof being generally both expensive and time-consuming.

Heretofore, paraffin deposits could be cleaned from an oil well production tubing by employing any one of several methods: by introducing chemicals into the production tubing to dissolve the paraffin, by lowering an electric heater into the tubing to melt the deposits, by dropping a wire-line go-devil into the tubing, or by attaching scraper knives to the sucker rod string in a pumping well. With the exception of the last-mentioned method, the use of any of the methods entails considerable lost production time in that it is necessary to shut down the well while its production tubing is being cleaned. In a like manner, it is necessary to shut a well down in order to install or replace paraffin cutting knives on a sucker rod string. Additionally, the installation of knives on several hundred feet of sucker rod string is very expensive.

Accordingly, it is a general object of this invention to provide a method for removing paraffin deposits from an oil well production tubing without stopping the flow of oil therethrough.

Another general object of this invention is to provide a method for removing paraffin deposits from an oil well production tubing, which method combines mechanical and hydraulic features in order to clean the tubing effectively.

A further object of the present invention is to provide a particularly effective and inexpensive method for cleaning the inner walls of a production tubing in a well while the well is being produced, thus utilizing the well flow to remove any paraffin particles from the well.

In accordance with this invention an elongated, flexible line, and particularly a flat ribbon steel wire is provided which is insertable into a well production tubing to be positioned against the inner wall thereof, whereby, upon relative rotational movement of the line and the tubing, the line is caused to move around the inner wall of the tubing and scrape the paraffin deposits therefrom throughout considerable vertical sections of the tubing as the well flow carries the scrapings to the surface. Hence, the scraping action of a weighted line suspended in the tubing and the hydraulic action of the pumped or flowing well fluid are both utilized to keep the inner surface of the production tubing free of paraffin deposits.

By combining in a single operation, mechanical and hydraulic action to remove material clogging a well production tubing, this invention makes possible more rapid and thorough removal of such material from the tubing. By subjecting the paraffin clogging the tubing to a combined mechanical and hydraulic action, the material broken up by the mechanical action is dislodged and

washed away quickly, rather than permitting it to fall to the bottom of the well again where it would again become dissolved in high temperature oil. In carrying out the present invention, a low cost paraffin scraper of simple construction may be used, which permits the attainment of the results desired at a great saving in operating cost and operating time.

The foregoing and other objects and advantages of this invention will be more readily understood by reference to the following description of specific apparatus which is particularly well suited for carrying out this invention. It is to be understood that the present method is applicable to other apparatus, such, for example, as the various embodiments disclosed and described in my copending patent application, entitled "Paraffin Scraper for Wells," Serial No. 222,708, which was filed April 24, 1951, now Patent No. 2,678,696. Various features and refinements of the present method will be understood from the following description in conjunction with the accompanying drawing, wherein:

Figure 1 is a diagrammatic view, partly in cross section, of the upper portion of a cased well including the well head assembly.

Figure 2 is a diagrammatic view, partly in cross section, of another well head assembly including means for rotating the production tubing.

Referring to Figure 1 of the drawing, the well bore 11 is shown to contain the usual casing 12 having a suitable well head assembly 13 flanged to its upper end. The well head assembly 13 may have any suitable number and arrangement of valves and fluid conduits, but for purposes of illustrating the present invention the head 13 is shown as being equipped with a single conduit 14 for discharging oil from the well casing.

Suspended from the well head 13, in any suitable manner well known to the art, is a production tubing 15 which is normally positioned concentrically in the casing 12. The top plate 16 of the well head assembly 13 is provided with an opening 17, coaxial with production tubing 15, said opening 17 being closed in a fluidtight manner by a suitable stuffing box diagrammatically represented at 18. Mounted above the stuffing box 18 on a pipe section 38 is a wire line hanger head 19 in which a wire line or scraping cable 20 may be fixedly secured in any suitable manner, as by riveting, bolting or the like. The hanger head 19 is closed at the top by a cap 21.

Affixed to the outer wall of the hanger head 19 is a ring gear 22 which is adapted to mesh with a drive gear 23. The drive gear 23 in turn is fixedly secured to a shaft 40 which is mounted in a bearing 24, and driven by a hand crank 25. It is to be realized that any suitable gearing arrangement, prime mover means or drive mechanism may be employed to rotate the hanger head 19 and the wire line 20. The wire line 20 may be of any cross-sectional shape, for example, square, round, hexagonal, flat rectangular or the like, and is of a length sufficient to extend from the top of the well down to a point in the production tubing 15 where paraffin begins to deposit. For cleaning production tubing by the method of the present invention, it has been found that especially good results have been obtained by employing a wire line having sharp longitudinal edges, such as a line made of flat ribbon steel, e. g., steel baling or banding tape, having any desired width such as $\frac{3}{8}$, $\frac{1}{2}$, $\frac{3}{4}$ inch, etc. In order to maintain a fixed tension on the line 20, a weight 26 of suitable dimension is secured to the lower end of the line.

In cleaning paraffin deposits from the inner wall of the production tubing 15, the drive gear 23 is turned by hand crank 25 to rotate ring gear 22, hanger head 19 and wire line 20. The wire line 20 may be moved around the inner wall of the production tubing at any desired speed, say, from one revolution a minute or one a day, depending on the amount of paraffin to be removed. As the paraffin particles are scraped from the production tubing 15 they are carried up the tubing 15 and out the discharge conduit 14 by the flowing stream of oil.

Instead of rotating the wire line 20 within the stationary production tubing 15, it may be readily seen that a tubing 27 may be rotated about a stationary wire line 28 as shown in the embodiment illustrated in Figure 2. In this embodiment, the well head assembly comprises a

cylindrical housing 29 in which an annular thrust bearing 30 is mounted, as on support members 31. Rotatably mounted on the thrust bearing 30 is a slip bowl 32 and slips 33 for supporting the production tubing 27 in the well casing 34 in a manner in which it may be rotated. The top of the housing 29 is closed in any suitable fluid-tight manner, as by rings of packing 35 between a junk ring 36 and a follower 37.

A swivel, diagrammatically shown at 39, is secured in the production tubing 27 above the well head assembly so that the tubing 27 below the swivel may be rotated while the portion of tubing above the swivel remains stationary. Above the swivel 27 the production tubing may comprise a short pipe section 41, a T 42 and a discharge conduit 43 leading to a storage tank or pipe line (not shown). A hanger head 44 closed at the top by a plug 45 is secured to the top of the T 42.

The wire line 28 is fixedly secured, as by rivets, to the inner wall of the hanger head 44 and preferably is affixed to the head 44 to one side of its vertical axis in a manner such that at least one and preferably both edges of the steel ribbon-tape wire line scrape along the wall of the production tubing as the latter is rotated. Since as a practical matter, an oil well is never perfectly straight, the production tubing 27 will generally be at some small angle to the vertical which will cause the wire line 28 to scrape along the inner wall of the tubing 27 even when the wire line is affixed to the center of the hanger head 44. As the tubing 27 is rotated about the wire line 28, the drag exerted by the tubing wall on the wire line causes the latter to be formed in a series of long spirals which effectively scrape the entire inner surface of the production tubing 27 free of paraffin or other deposits.

In order to rotate the production tubing 27 extending below the swivel 39, a drive wheel 46 is provided which is fixedly secured to said tubing 27 between the swivel 39 and the well head assembly 29. Any suitable mechanical, electrical, pneumatic or hydraulic prime mover means 47 may be connected through suitable transmission means, as through a worm gear 48 to drive wheel 46 and rotate the production tubing 27. In operation, the production tubing 27 is rotated very slowly, for example, one or more revolutions a day depending upon well conditions while the wire line 28 remains substantially stationary.

From the above described embodiments it may be seen that the present method of removing paraffin from an oil well production tubing may be employed in a well when either the wire line or the production tubing are rotated. Thus, a method is provided for simultaneously removing paraffin deposits from the bore of a production tubing throughout its entire length or any desired portion thereof. Hence, if the well temperature at the 2000 ft. level is sufficiently low enough to cause paraffin deposition within the bore of the production tubing over the 0 to 2000 ft. interval, the present steel scraping tape may be run into the tubing to the 2000 ft. level whereby the paraffin may be removed upon rotation of the production tubing and scraping tape with regard to each other. Thus, a method is provided for cleaning production tubing without the necessity of reciprocating either the tubing or the

scraper as when sucker rod scrapers are used. Additionally, the present method employs a relatively inexpensive light weight steel tape suspended in the tubing instead of a large number of expensive, heavy rotary or reciprocating cutters as are needed in conventional methods of paraffin removal.

From the apparatus described in my copending application Serial No. 222,708 entitled: "Paraffin Scraper for Wells," filed April 24, 1951, it may be seen that the present paraffin removal method may be employed in both naturally flowing or pumping wells, as well as wells produced by the gas lift method. Pumping wells include those using pumps activated by either a reciprocating production tubing or a sucker rod string. Where a string of sucker rods is employed, the diameter or width of the wire line is of a size sufficient to pass through the annular space between the sucker rods and the inner wall of the production tubing. While the present paraffin removal method may be employed to remove paraffin deposits when a well is not being produced, it is preferred that a flow of oil be maintained through the production tubing as its inner wall is scraped whereby the oil flow carries the paraffin particles out of the well. From the above description it may be seen that the above method of removing paraffin is especially advantageous when it is desired to clean the production tubing without interrupting production from the well. Removal of paraffin deposits permits a well to be produced at a rate equal to the maximum throughput of the production tubing, i. e., at maximum efficiency.

I claim as my invention:

A method of removing deposits of paraffin or asphaltic bodies from the inner surface of a production tubing positioned within a well, said method comprising the steps of introducing into said production tubing from the top thereof to a point at least level with said deposits an elongated metallic flexible line weighted at its lower end, scraping all deposits from the inner wall of said tubing by producing relative movement between said flexible line and said tubing by moving said line in an orbital path along the inner wall of said tubing, and simultaneously flowing the well fluid upwardly through said production tubing to remove the loosened deposits from the tubing.
